UNITED STATES PATENT OFFICE.

WILLIAM T. SHERER, OF CHICAGO, ILLINOIS.

SHELF-LABEL.

1,284,796.

Specification of Letters Patent. Patented Nov. 12, 1918.

Application filed March 11, 1918. Serial No. 221,608.

To all whom it may concern:

Be it known that I, WILLIAM T. SHERER, a citizen of the United States, residing at Chicago, in the county of Cook and State 5 of Illinois, have invented a certain new and useful Improvement in Shelf-Labels, of which the following is a specification.

My invention relates to improvements in label supports which are easily fastened in place, moved or removed. It has for an object to provide a simple, easily applied shelf label which can with little effort be slipped into place on a shelf but which when in place will firmly hold its position and will 15 not slip or be displaced by a chance rub or blow.

Another object is to provide a firm holding label support which is easily removable.

My invention is illustrated more or 20 less diagrammatically in the accompanying drawings wherein—

Figure 1 is a front elevation of shelves with my label support in place thereon;

Fig. 2 is a cross section of a shelf with 25 my label support in place;

Fig. 3 is a cross section of a shelf with the label support about to be placed in position;

Fig. 4 is a rear elevation of the support showing the fastening means;

Fig. 5 is a cross section of a modified form 30 of my invention in place on a shelf.

Like parts are indicated by like letters in all the figures.

A is a label support of metal or other suitable material adapted to be fastened to shelves B and the like by means of flanges C and D. The support A is preferably made broader than the thickness of the shelf or board or projection against which it is to fit.

The upper flange C extends at a right angle 40 from the label and fits snugly against the top surface of the shelf. It will be understood that if the top of the shelf and the front surface of the shelf are at an angle

other than a right angle the relation of the flange and the label can be modified to conform thereto. The lower flange D may be of any suitable shape but I prefer to have it so shaped that it will not engage

the shelf intermediate the label and the end 50 of the flange, and that it will be yielding or flexible so that the inner end of the lower flange and the upper flange may be closer together than the thickness of the shelf

when the device is not in operation. Thus 55 there will be a yielding pressure tending to

hold the clamp or holder in position on the shelf. The inner end of the flange is upturned to form a holding blade E terminating in a plurality of teeth F which grip 60 the lower side of the shelf. In the preferred form of my invention the lower flange D is so shaped as to form with the label itself a downwardly depending fold G which can serve as a handle to remove the label. The 65 holding blade E is preferably inclined forward toward the label to give the maximum hold on the shelf. It will be understood that the irregularly formed flange could be placed above the shelf were there need for 70 such arrangement or that both flanges might be formed to grip the shelf only at their ends when there is any advantage thereby to be obtained.

In the modified form shown in Fig. 5, the 75 depth of the flange X is much less than the depth of the flange C and the flange X¹ with its forwardly extending toothed holding plate X² is shorter and thus somewhat stiffer though still you get the spring effect. The 80 point of this arrangement is that the parts are so positioned that you first can engage the toothed edge and then rotate the carrier about the engaging point bending it slightly as it engages the shelf and it will finally 85 snap into position without movement of the toothed portion with respect to the shelf. Thus this device can be put in place with less damage to the shelf surface since there is no sliding contact of any cutting part 90 upon the shelf.

It will be evident that while I have shown in my drawings an operative device, still many changes might be made both in size, shape and arrangement of parts without departing materially from the spirit of my invention and I wish, therefore, that my drawings be regarded as in a sense diagrammatic. 95

The use and operation of my invention are as follows:—

When it is desired to fit the label to a shelf the lower flange with its inclined gripping blade is placed in contact with the lower surface of the shelf and the whole label is turned on the holding blade as a pivot. 105 With the length of flange shown in Figs. 2 and 3, it will be necessary further to press the label in place but with the form shown in Fig. 5 the mere revolution of the label on the holding blade will fit it in place. The 110 holding blade being inclined toward the label it will firmly hold the label in place

although it will present no resistance to the placing of the label. When it is desired to withdraw the label, the operator by pulling outwardly on the handle formed by the lower 5 part of the label and the bent portion of the lower flange can pull the holding blade away from the bottom of the shelf and remove the whole label without difficulty, or the upper forward portion of the carrier 10 may be engaged and it may be rotated about the line of engagement as an axis and gradually slid forward at the same time thus making it possible to take it off with practically no sliding movement of the upper 15 flange upon the top of the shelf and with little if any sliding movement of the toothed holding portion on the bottom of the shelf.

I claim:

As a new article of manufacture, a shelf 20 clamping tag holder comprising a plate of thin spring sheet metal of an irregular U shape, the bottom adapted to engage the

edge of the shelf and extend below the same and to hold the tag, the upper limb adapted to overlie the forward part of the shelf surface, and the lower limb upwardly bent and provided at its edge with teeth turned toward the bottom so as to permit the holder to be easily slipped into position and to resist motion away from the shelf, the distance between the two limbs and their length being such that the holder can be rotated about the toothed edge when the latter is in position on the bottom of the shelf so as to bring the upper limb into proper position without materially sliding the toothed portion along the shelf in either direction.

In testimony whereof, I affix my signature in the presence of two witnesses this 7th day of March, 1918.

WILLIAM T. SHERER.
